CLAIM

The ornamental design for an interlocking panel for a jewelry rack, as shown and described.

DESCRIPTION

FIG. 1 is a front perspective view of an interlocking panel for a jewelry rack showing our new design; FIG. 3 is a rear perspective view, the broken line showing of a second panel being for illustrative purposes only;

FIG. 4 is a right side elevational view;

FIG. 5 is a left side elevational view;

FIG. 6 is a top plan view; and,

FIG. 7 is a bottom plan view thereof.
